UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

1,425,326.

Specification of Letters Patent. Patented Aug. 8, 1922.

Application filed September 10, 1920. Serial No. 409,323.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to typewriting machines in which a central type-guide is provided near the printing-point, and in which the types are provided with projections adapted to enter said guide which is usually placed in vertical alignment with the printing-point.

It is necessary to bend the type-bars, adjacent the type-heads, to a greater degree the nearer they approach the ends of the usual segment in order that the types 20 thereon may be in vertical alignment with the printing point on the platen. It has been found that the type-bars at the extreme ends of the segment had to be bent to such a degree as to impair the effectiveness 25 of the central guide. In addition to the central guide, there have, therefore, been provided auxiliary side-guides, as set forth in the application of George W. Campbell, Serial No. 325,928, filed September 24, 1919.

The present invention provides a new structure for the type-guide, having a central and two auxiliary side-guides, and also provides means whereby the width of the guides may be adjusted, and the guides then locked.

The type-guide of the present invention may constitute a new article of manufacture comprising a base or attaching portion, a central pair of spaced jaws rising therefrom and forming a central guide-slot, and two lateral or outer pairs of spaced jaws carried by the respective jaws of the first or central pair and forming lateral guide-slots disposed at a radial angle to the central guide-slot and to each other, together with separate means for independently adjusting each pair of jaws to vary the width of the guide-slots.

Other features and advantages will hereinafter appear.

In the accompanying drawings,

Figure 1 is an end view of a bracket provided with the central and auxiliary type-

guides and applied to the machine (only part of which is shown). 55

Figure 2 is a front view of the structure shown in Figure 1.

Figure 3 shows the device dissociated into its various parts and disconnected from the machine. 60

Figure 4 is a front view of a modified form looking in the direction of the arrow in Figure 5.

Figure 5 is an end view of the device shown in Figure 4. 65

Figure 6 is a detail section of one of the beveled-head adjusting screws taken on the line 6—6 of Figure 4.

The machine comprises the usual type-bars 10, pivoted upon a fulcrum rod 11, and operated by the usual key-levers (not shown.) The type-bars operate in a segment 12, having radial guide-slots 13 for the type-bars 10. Each of the type-bars carries a type-block or type-head 15 bearing (in this instance) three types 16. In the ordinary typewriter, each typeblock has a projection 17 in line with the type and adapted to operate in a guide-slot 18 of the type-guide. The latter comprises a base-forming bracket or attaching portion 20 fixed to the segment by means of screws 21, and consists of an upstanding portion 24 having risers 25 providing jaws spaced apart to form a central guide-slot 18. The 85 risers end in lugs or flanges 19, forming lower jaws, each presenting a flat upper surface inclined substantially radially from the printing-point, which is slightly above the tops of the risers, the type striking 90 against the platen 30. Each riser is provided in its outer side with tapped holes 31 and 32. In addition the left-hand riser has a tapped hole 33, while the right-hand riser has a corresponding clearance hole 34. 95

Adapted to be attached to the risers are side members 36 having inclined upper flanges 37, forming upper jaws, which run in the same direction and are of the same form as the flanges or lower jaws 19 on the 100 risers. The side members are adapted to be held in position so that the upper flanges 37 are spaced above lower flanges 19 a distance equivalent to guide space 18, or slightly more than the thickness of the type-bar, thereby to form auxiliary guide-slots. 105

- The side members are each provided with a vertically elongated slot 40 in register with tapped hole 31, and a beveled notch 41 at the lower extremity co-operating with 5 tapped hole 32. The side members are of such width and shape as not to interfere with holes 33 and 34. The attachment of members 36 to the risers is effected by means of a flat-head screw 43 passing through 10 slot 40 and engaging tapped hole 31, and a beveled-head screw 42 passing through notch 41 and engaging tapped hole 32. It will be seen that flanges 37 and 19 form 15 spaced upper and lower jaws, respectively, and are the auxiliary guides. The width of these guides may be adjusted by raising or lowering the side members. This is accomplished by loosening screws 43 and screwing beveled-head screws 42 in or out 20 of notches 41 as desired to raise or lower the side members, since the latter ride upon the bevel of screws 42. The side members are then locked in position by means of the screws 43.
- 25 The adjustment of the central guide is accomplished by means of a pair of screws, either of which may be the adjusting screw or the locking screw. A screw 45, extending from one jaw 25 to the other, passes through 30 clearance hole 34 and engages the screw-threads in the tapped hole 33. It will be seen that the action of this screw will be to draw the jaws together. The other screw is a beveled-head screw 50 (similar to the 35 screw 62 shown enlarged in Figure 6) passing or entering between the jaws and having threaded engagement with the inner walls of the jaws, the adjusting screws 45 and 50 being disposed transversely or at 40 right-angles to each other. It will be apparent from Figure 6 that upon entrance of the beveled head between the jaws the latter will be spread apart. The adjustment is accomplished as follows: Assuming that the 45 jaws are too close together, the beveled-head screw 50 is screwed in to spread the jaws apart, the screw 45 being first released or loosened. When the desired opening has been obtained screw 45 is tightened and 50 will prevent the jaws from moving out of this position, and so serves to lock the jaws in adjusted position. Assuming that the jaws are too far apart, screw 50 is released, and screw 45 is screwed in until the jaws 55 are drawn together the desired distance. The screw 50 is then tightened and serves to prevent further drawing together of the jaws, thus locking the jaws in adjusted position.
- 60 In Figures 4 and 5 is illustrated a modification of the device described above. In this case the auxiliary guides are formed on the risers and there are no adjustable side members. It is the equivalent of making 65 side members 36 and risers 25 integral. The

adjustment of the auxiliary guides does not, therefore, depend upon movable side members. The risers carry both jaws of the auxiliary guides 60, while the central guide is the same as the Figures 1, 2 and 3 species. 70 The adjustment of all of the guides is accomplished in the same manner as the central guide of the Figures 1, 2 and 3 device, i. e., by two screws, either one serving as the adjustment screw while the other is the locking screw. Screw 61 passes through a clearance hole in one jaw and engages a tapped hole in the other. Beveled-head screw 62 passes or enters between and engages the screw-threaded interior walls of the jaws. 80 The adjustment of any of the guides is accomplished in the same manner as described above in connection with the central guide of Figures 1, 2 and 3.

The advantages of the auxiliary slots are 85 sufficiently set forth in the Campbell application previously referred to. Since the type-blocks 15 must strike the printing-point in a vertical line, it is apparent that the type-blocks near the ends of the segment 90 12 must be turned on their type-bars 10 an increasingly greater degree as they approach the ends of the segment. Such bent type-bars tend to rattle or spring laterally and their efficiency is thus impaired. 95 The auxiliary guides obviate this objection. Several keys at each end of the segment utilize the auxiliary guides, flat guiding projections 65 being provided on the type-bars 100 to enter such auxiliary guides. By making the guides adjustable a more perfect co-operation can be obtained with the type-bars and hence a smoother operation of the machine, as well as a more nearly perfect 105 alignment and spacing of the printed characters along the printing line on the platen, thereby improving the quality of the work.

In the particular construction or embodiment of the invention illustrated in Figures 1 to 3, inclusive, of the drawings, and forming a new article of manufacture, the base or attaching portion 20, the upstanding central pair of jaws 25 and the inner members or jaws 19 of the lateral or outer pair of jaws, are all formed integrally or in one 110 piece, while the outer jaws 37 of the outer or lateral pair of jaws form parts of the separate attachable members 36. In the modified construction forming the new article of manufacture illustrated in Figures 115 4 and 5, the auxiliary guides 60, forming the outer or lateral pair of jaws, are carried by the upper ends of and formed in one piece with the central pair of jaws and with the base or attaching portion of the 120 device. In both these varieties of the new article of manufacture, and as hereinbefore particularly described, separate means are provided for independently and relatively 125 adjusting the jaws of each pair to vary the 130

width of the guide-slot formed between the jaws.

Variations may be resorted to within the scope of the invention, and portions of the improvements may be used without others.

Having thus described my invention, I claim:

1. A type-guide for the types of a type-writing machine forming a new article of manufacture and comprising a base or attaching portion, a central pair of spaced jaws rising therefrom and forming a central guide-slot, two lateral pairs of spaced jaws carried by the respective jaws of said central pair of jaws and forming lateral guide-slots disposed at a radial angle to the central guide-slot and to each other, and separate means for independently relatively adjusting the jaws of each pair of jaws to vary the width of each of the guide-slots.

2. A type-guide for the types of a type-writing machine forming a new article of manufacture and comprising a base or attaching portion, a central pair of spaced jaws rising therefrom and forming a central guide-slot, two lateral pairs of spaced jaws carried by the respective jaws of said central pair of jaws and forming lateral guide-slots disposed at a radial angle to the central guide-slot and to each other, and separate means for independently relatively adjusting the jaws of each pair of jaws to vary the width of each of the guide-slots; the base or attaching portion, the central pair of jaws and the inner jaws of the lateral pairs of jaws all being formed in one piece, and each of the outer jaws of the lateral pairs of jaws being formed as separate pieces attachable to the respective jaws of the central pair of jaws.

3. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to enter said guide, type-bar guides near the printing-point and at the sides of said central type-guide and auxiliary thereto, to be directly engageable by type-bars at the sides of the system, and means on said central and auxiliary guides for adjusting the width thereof.

4. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to en-

ter said guide, type-bar guides near the printing-point and at the sides of said central type-guide and auxiliary thereto, to be directly engageable by type-bars at the sides of the system, said side type-bars having bends at their type ends, said auxiliary guides being engageable by said type-bars between said bends and the type-bar pivots, said side type-bars being provided with guiding projections extending directly therefrom to enter said auxiliary type-guides, and means on said central and auxiliary guides for adjusting the width thereof.

5. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to enter said guide, a bracket upon which said central guide is mounted, risers on said bracket extending upward from the central guide at the sides thereof and provided with jaws to form auxiliary guides, one on each side of and above the central guide and engageable by type-bars at the sides of the system, and means on said central and auxiliary guides for adjusting the width thereof.

6. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to enter said guide, a bracket upon which said central guide is mounted, risers on said bracket extending upward from the central guide at the sides thereof and provided with jaws to form auxiliary guides, one on each side of and above the central guide and engageable by type-bars at the sides of the system, said jaws inclining substantially radially from printing-point, and means on said central and auxiliary guides for adjusting the width thereof.

7. In a front-strike typewriting machine, in combination, a platen, a system of pivoted type-bars normally occupying a substantially horizontal position in the arc of a circle and radiating substantially from the printing-point on the front of the platen in the printing position of the type-bars, type-carrying type-heads on the forward ends of the type-bars arranged in varying angles thereto for bringing the types into vertical alignment with the printing-point in the printing position of the types, a central type-guide at the front of the platen and having a guide-slot in vertical alignment

- with the type-heads of the main or middle portion of the type-bars in the system in the printing position of these type-heads, guiding projections extending from the type-heads of said main portion in line with the type-heads to enter the guide-slot of the central type-guide, auxiliary type-guides near the printing-point and at the sides of the central type-guide and having guide-slots to be directly entered by the type-bars at the sides of the system and near the type-heads, and separate means for independently adjusting the width of the guide-slots of said central and auxiliary guides.
- 5 10 15 20 25 30 35 40 45 50 55 60
16. In a front-strike typewriting machine, in combination, a platen, a system of pivoted type-bars normally occupying a substantially horizontal position in the arc of a circle and radiating substantially from the printing-point on the front of the platen in the printing position of the type-bars, type-carrying type-heads on the forward ends of the type-bars arranged in varying angles thereto for bringing the types into vertical alignment with the printing-point in the printing position of the types, a central type-guide at the front of the platen and having a guide-slot in vertical alignment with the type-heads of the main or middle portion of the type-bars in the system in the printing position of these type-heads, guiding projections extending from the type-heads of said main portion in line with the type-heads to enter the guide-slot of the central type-guide, auxiliary type-guides near the printing point and at the sides of the central type-guide and having guide-slots to be directly entered by the type-bars at the sides of the system and near the type-heads, said type-bars at the sides of the system being provided with flat guiding projections extending directly therefrom to enter the guide-slots of the auxiliary type-guides, and separate means for independently adjusting the width of the guide-slots of said central and auxiliary guides.
17. In a front-strike typewriting machine having a platen, a system of pivoted type-bars normally occupying a substantially horizontal position in the arc of a circle and radiating substantially from the printing-point on the front of the platen in the printing position of the type-bars, said type-bars carrying types at their forward ends; in combination with a type-guide comprising an attaching base fixed on the machine, a central pair of spaced jaws rising from the attaching base and forming a substantially vertical central guide-slot for the types carried by the main or middle portion of the type-bars in the system, two lateral pairs of spaced jaws carried by the respective jaws of said central pair of jaws and forming lateral guide-slots disposed at a radial angle 65 to the central guide-slot and to each other for guiding the types carried by the type-bars at the sides of the system, and separate means for independently relatively adjusting the jaws of each pair of jaws to vary the 70 width of the guide-slot formed thereby.
18. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to enter said guide, type-bar guides near the printing-point and at the sides of said central type-guide and auxiliary thereto, to be directly engageable by type-bars at the sides of the system, said side type-bars having bends at their type ends, said auxiliary guides being engageable by said type-bars between said bends and the type-bar pivots, and means on said central and auxiliary guides for adjusting the width thereof.
19. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to enter said guide, a bracket upon which said central guide is mounted, risers on said bracket forming the central guide and provided with jaws to form auxiliary guides, one on each side of the central guide and engageable by type-bars at the sides of the system, and means on said central and auxiliary guides for adjusting the width thereof.
20. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to enter said guide, a bracket upon which said central guide is mounted, risers on said bracket forming the central guide and provided with jaws to form auxiliary guides, one on each side of the central guide and engageable by type-bars at the sides of the system, and means on said central and auxiliary guides for adjusting the width thereof.
21. In a front-strike typewriting machine, the combination with a system of pivoted type-bars, of a central type-guide for the main portion of the type-bars in the system, said central guide being in a line with the types at the printing-point, and said main type-bars having types provided with guiding projections extending therefrom to enter said guide, a bracket upon which said central guide is mounted, risers on said bracket forming the central guide and provided with jaws to form auxiliary guides, one on each side of the central guide and engageable by type-bars at the sides of the system, said jaws inclining substantially radially from the printing-point, and means on said central and auxiliary guides for adjusting the width thereof.
22. In a front-strike typewriting machine, the combination with a system of pivoted type-bars, of a bracket fixed to said machine, risers forming a central type-guide and also forming lower jaws, one on either side of

- said guide, members adapted to be attached to said risers and forming upper jaws, said lower and upper jaws co-operating to form auxiliary guides, one to either side of the 5 central guide, each of said guides co-operating with certain of the type-bars, and means for adjusting said members on the risers to vary the distance between the upper and lower jaws.
- 10 14. In a front-strike typewriting machine, the combination with a system of pivoted type-bars, of a bracket fixed to said machine, a central type-guide on the bracket comprising spaced jaws forming a central guide- 55 slot, risers on said bracket, one on either side of and forming the central guide and also forming lower jaws, members adapted to be attached to said risers and forming upper jaws, said upper and lower jaws co- 60 operating to form auxiliary guides, one to either side of the central guide and forming auxiliary guide-slots, each of said guides co-operating with certain of the type-bars, and means on each of said guides for adjusting 65 the distance between the jaws thereof to vary the width of the guide-slot.
- 15 15. In a front-strike typewriting machine, the combination with a system of pivoted type-bars, of a bracket fixed to said machine, a central type-guide on the bracket comprising spaced jaws forming a central guide-slot, 70 risers on said bracket, one to either side of and forming the central guide and also forming lower jaws, members adapted to be attached to said risers and forming upper jaws, each member having an upper 75 slot and a cut-out portion in its lower extremity, said upper and lower jaws co-operating to form auxiliary guides, a beveled-head screw co-operating with the cut-out portion of each side member and one of the tapped holes of each riser to adjust the side member vertically, and a screw passing through the slot in each side member and co-operating with the other tapped hole to lock the side member in adjusted position, said slots being elongated to allow for relative movement of the side members and risers to adjust the distance between said upper 80 and lower jaws.
- 20 17. In a front-strike typewriting machine, the combination with a system of pivoted type-bars, of a bracket fixed to said machine and comprising a central type-guide and risers, one to either side of said guide and forming lower jaws, each of said risers having two tapped holes, side members adapted to be attached to said risers and forming upper jaws, each member having an upper 85 slot and a cut-out portion in its lower extremity, said upper and lower jaws co-operating to form auxiliary guides, a beveled-head screw co-operating with the cut-out portion of each side member and one of the tapped holes of each riser to adjust the side member vertically, a screw passing through the slot in each side member and co-operating with the other tapped hole to lock the side member in adjusted position, said slots 90 being elongated to allow for relative movement of the side members and risers to adjust the distance between said upper and lower jaws, the central guide having a screw passing between the jaws and having threaded engagement therewith for spreading the jaws apart, one of said jaws having a tapped hole, the other of said jaws having a corresponding clearance hole, and a screw passing through the clearance hole and co-operating 95 with the tapped hole to draw the jaws together, each of said screws being adapted to lock the jaws in position when the other screw is used for adjustment purposes.
- 25 16. In a front-strike typewriting machine, the combination with a system of pivoted type-bars, of a bracket fixed to said machine and comprising a central type-guide and risers, one to either side of said guide and forming lower jaws, each of said risers having two tapped holes, side members adapted to be attached to said risers and forming upper jaws, each member having an upper 100
